ville, Ind., a corporation of Indiana
No Drawing. Filed Dec. 9, 1964, Ser. No. 417,246
5 Claims. (Cl. 260—243)

This invention relates to novel chemical compounds having pharmaceutical utility, with the preparation of these substances and with their pharmaceutical use.

In accordance with the present invention it has been found that certain acyloxy-2-aryl-1,3-thiazinones have effective uricosuric activity. The compounds of the invention, for purposes of description, can be represented by general Formula I:

wherein A and B are different and are selected from the group consisting of O= and

with R being an alkyl group of one to four carbon atoms and X and Y are selected from the group consisting of hydrogen, halogen, nitro, alkoxy and alkyl having up to four carbon atoms.

The novel uricosuric agents are prepared by a process which comprises heating a 2-aryl-5,6-dihydro-4H-1,3-thiazine-4,6-dione having the formula

TABLE I.—EXAMPLES II-XIII

¹ Corrected melting points, °C.—^a Heptane, ^b Acetonitrile, ^c Isopropyl Acetate, ^d Ethyl Acetate, ^e MeOH.² Compound III was obtained by reacting 4-chlorothioacetamide with malonic acid in acetic anhydride; yield calculation based on the thioamide.³ Chlorine analysis.

One reliable index of uricosuric activity is the ability of the test compound to induce retention of phenol red in the circulatory system of a rat. The compounds embraced by the present invention were tested for this ability. In these tests, adult albino rats of either sex were pretreated with the test compound orally 15 minutes before being anesthetized with dial-urethane (0.5 milliliter per kilogram, intraperitoneally). Fifteen minutes later each rat received via the caudal vein 75 milligrams of phenol red per kilogram as a 1.5% solution in 0.9% sodium chloride. Then, 30 and 60 minutes after dye injection blood samples were taken from the retro-orbital plexus into heparinized capillary tubes which were then centrifuged. The amount of phenol red remaining in plasma was determined by transferring, via Sahli pipettes, 0.02 milliliter aliquots of plasma into 12 x 75 millimeter Coleman cuvettes containing 1.5 milliliters of 0.1 N sodium hydroxide and read against blanks containing plasma, saline, and 0.05 milliliter of 0.1 N hydrochloric acid at 540 m μ on the Coleman Jr. spectrophotometer. Micrograms of phenol red remaining per milliliter of plasma were calculated from optical density reading and a previously determined standard curve.

TABLE II

Oral MRD¹

mg./kg.

Product of:	mg./kg.
Example II	12.5
Example I—Lot 1	6.3
Example III	50
Example IV	25
Example V	100
Example IX	100
Example X	100

¹ MRD=minimum retentive dose; lowest mg./kg. dose tested which produced significant retention of phenol red in plasma of rats receiving test compound orally 30 minutes prior to dye injection.

For purposes of comparison one of the best known uricosuric agents which is presently in clinical use exhibits MRD (minimal retentive dose) values in the phenol red retention test of 12.5-25 milligrams per kilogram.

The uricosuric agents of the invention can be administered orally to humans in the treatment or prevention of gout to increase uric acid secretion. For this purpose dosages from about 50-100 milligrams per day can be employed. Dosage unit forms of the active uricosuric agent such as capsules, powders, tablets and liquids containing from 25 to 100 milligrams of the active agents are convenient for administration in dosages in this range.

As used herein the formula

is a generic formula which embraces compounds of the following formulae:

wherein A, B, X and Y are as previously indicated.

Those modifications and equivalents which fall within the spirit of the invention and the scope of the appended claims are to be considered part of the invention.

We claim:

1. An acyloxy-2-phenyldihydro-1,3-thiazinone having the formula

wherein A and B are different and are selected from O= and

R is an alkyl group of from 1 to 4 carbon atoms, and X and Y are selected from hydrogen, halogen, nitro, alkoxy of up to 4 carbon atoms, and alkyl of up to 4 carbon atoms.

2. A compound in accordance with claim 1 wherein R is C₂H₅.

3. A compound in accordance with claim 1 wherein R is CH₃.

4. A compound in accordance with claim 1 wherein R is C₂H₅ and X and Y are hydrogen.

5. A compound in accordance with claim 1 wherein R is CH₃ and X and Y are hydrogen.
